Primary Examiner — Keli L Hill*Assistant Examiner* — Harold E Blackwell, II(74) *Attorney, Agent, or Firm* — Muncy, Geissler, Olds & Lowe, P.C.(57) **CLAIM**

The ornamental design for an antenna base, as shown and described.

DESCRIPTION

FIG. 1 is a front plan view of an antenna base showing my new design;

FIG. 2 is a rear plan view thereof;

FIG. 3 is a left side plan view thereof;

FIG. 4 is a right side plan view thereof;

FIG. 5 is a top plan view thereof;

FIG. 6 is a bottom plan view thereof;

FIG. 7 is a front perspective view thereof; and,

FIG. 8 is a rear perspective view thereof.

The broken lines illustrate portions of the antenna base that form no part of the claimed design.
